(57) **CLAIM**

The ornamental design for a “human body detector,” as shown and described.

DESCRIPTION

FIG. 1 is a right, front perspective view of a “human body detector;”

FIG. 2 is a front view of the “human body detector” of FIG. 1; FIG. 3 is a rear view of the “human body detector” of FIG. 1; FIG. 4 is a right side view of the “human body detector” of FIG. 1;

FIG. 5 is a left side view of the “human body detector” of FIG. 1;

FIG. 6 is a top view of the “human body detector” of FIG. 1; FIG. 7 is a bottom view of the “human body detector” of FIG. 1;

FIG. 8 is a right, front perspective view of the “human body detector” of FIG. 1 including a mounting assembly;

FIG. 9 is a front view of the “human body detector” of FIG. 8; FIG. 10 is a rear view of the “human body detector” of FIG. 8;

FIG. 11 is a right side view of the “human body detector” of FIG. 8;

FIG. 12 is a left side view of the “human body detector” of FIG. 8;

FIG. 13 is a top view of the “human body detector” of FIG. 8; and,

FIG. 14 is a bottom view of the “human body detector” of FIG. 8.

The features shown in broken lines are for illustrative purposes only and do not form part of the claimed design.
